UNITED STATES PATENT OFFICE.

GEORGE GOULD GOING, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,277,209.

Specification of Letters Patent. Patented Aug. 27, 1918.

Application filed March 31, 1916. Serial No. 87,913.

To all whom it may concern:

Be it known that I, GEORGE GOULD GOING, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and more particularly to improved paper feeding mechanism and associated 15 parts thereof.

One of the objects of the invention is to provide a simplified and efficient construction of paper feed rollers and guide clips associated with a rotatable platen on the 20 traveling carriage.

A further object is to provide improved means for effecting movement of all the feeding and guiding rollers away from the platen roll when it is desired to adjust the 25 paper without rotating the platen.

Other objects and advantages will be in part obvious and in part noted hereinafter in connection with a description of the accompanying drawings, which illustrate a 30 typical embodiment of the invention.

The invention accordingly consists in the features of construction, combinations of elements and arrangement of parts which will be exemplified in the construction hereinafter set forth, and the scope of the application of which will be indicated in the following claims.

In the drawings—

Figure 1 is a front view of the major parts of a typewriter carriage;

Fig. 2 is a partial top view thereof;

Fig. 3 is an end view of Fig. 1 in the direction of the arrows;

Fig. 4 is a sectional view on the line 4—4 of Fig. 1; and

Fig. 5 is a front view of certain detached parts of Fig. 1.

The invention relates to parts associated with the traveling carriage of a typewriter, including a rotatable platen roll having cooperative therewith a plurality of sets of relatively small spring-pressed feed rollers and guide rollers. In the drawings the invention is illustrated as embodied in a noiseless typewriter, but it is to be understood

that certain features of the invention are susceptible of application with equal advantage to various other styles of machines.

Referring more particularly to the drawings, there is shown a traveling carriage 60 having end plates 1, 1' with a cross piece 2, and mounted for longitudinal letter-space movement and vertical case-shifting movement on a rail 3. A platen roll 4 is rotatably mounted in the end plates 1, 1', and is 65 provided with extending operating knobs 5 for manipulation. A suitable operating lever 6 is also mounted at the left end of the carriage and provided with a pawl 7 to engage ratchet wheels 8" keyed to the axial 70 shaft of the platen, whereby simultaneous line-space rotation of the platen and return movement of the carriage to line-commencing position is permitted in a well understood manner.

Extending parallel to the platen roll and positioned therebelow are two supporting spindles 8 and 8' fixed in the end plates 1, 1' and having journaled thereon a plurality, in this instance four, of sets of brackets 9 80 shaped as bell crank levers and carrying on their upper arms 10 rotatable feed rollers 11. The other arms 12 of the brackets 9 extend toward each other and beneath the platen and are engaged by the forked extremities of leaf springs 13 in a manner to resiliently urge the feed rollers against the platen. The arms 12 of the brackets are preferably curved in cross section, as shown in Fig. 5, and pressed against a longitudinally 90 slidable actuating strip 14 which rests on the upper surface of the carriage rail bearing 15. This sliding member is provided with a series of upwardly bent cam portions 16 contiguous to and below the adjacent arms 12 of the respective pairs of roller brackets 9. The slide 14 is also normally biased toward the left of the carriage by a spring 17 confined between the end wall 1' of the carriage and an upstanding lug 18 100 of the slide. At its opposite end the slide is provided with a roller bearing 19 journaled about a vertical axis.

The association of the cam 16 with the spring-pressed arms 12 of the feed roller 105 brackets is such that, upon movement of the slide 14 toward the right, said bracket arms are upraised against the action of the leaf spring tines, and the brackets accordingly rotate on their supporting spindles 8, 8', or 110

away from the platen roll 4. For effecting this movement of the member 14 there is provided, at the left of the carriage, an operating handle 20 pivoted adjacent its 5 lower end to the end plate 1 and terminating in a flattened extremity 21 disposed within a V-shaped recess 22 of an upturned end of a lever 23 extending parallel to the slide 14 and pivoted medially on a screw bolt 24. 10 The opposite end of the lever 23 is rounded to a point and contacts with the roller bearing 19, which normally maintains the cast-off operating lever 20 in the position shown in Fig. 4. Actuation of this lever 20 rearward at right angles to the axis of the platen roll rotates the sub-lever 23, which in turn, by its engagement with the roller bearing 19, moves the slide 14 to the right to raise the arms 12 and brackets 9, as described. 15 20 This movement of the operating lever is permitted to an extent which carries the inner end of the sub-lever 23 slightly beyond the diametrical line of the roller 19 parallel to the platen axis, so that the force of the 25 spring 17 yieldingly retains the parts in position with the feed rollers out of contact with the platen roll, whereby free adjustment of the paper is permitted.

There is also provided a longitudinal strip 20 extending parallel with the platen roll and preferably slightly below the forward feed rollers. This strip is carried by stampings 26 pivotally supported, at their rear ends, on the forward spindle 8 of the feed 25 roller brackets. On this strip a pair of paper guide clips 27 are slidably mounted, the connection between these parts preferably comprising spaced bent ears 28, which are turned over the edges of the member 25 40 in a manner affording free longitudinal adjustment of the clips. The clips also carry, at their upper extremities, paper guiding and tensioning rollers 29 which are normally urged into contact with the platen roll by 45 coil springs 30 extending beneath the latter and tensioned between the rear spindle 8 and off-set lugs 31 of the stampings 26. The stampings 26 are also provided with adjustable set screws 32 having conical extremities 50 disposed beneath the arms 10 of the corresponding brackets 9. The position of the set screws 32 is such that when the cast-off lever 20 is operated and the paper feed rollers are moved radially out of contact with 55 the platen roll, the corresponding roller bracket arms 10 engage with the set screws in their movement and move the strip 25 about its supporting axis to carry the paper clip rollers therewith out of contact with 60 the platen. By this arrangement the paper to be adjusted is freed from engagement by the feed rollers and paper clips jointly so that its manipulation is facilitated.

There is also provided, at each end of the 65 carriage, an escapement releasing lever 33

pivoted on the rear spindle 8' and having a bent lower arm 34 normally resting within the V-shaped recess of an angular arm 35 connected at its lower front end to the underside of the carriage escapement rack 36, 70 whereby, upon depression of the upper forward end of either release lever 33, an arm 35 is forced rearward and the escapement rack swung upward to clear the teeth of a normally intermeshing rotatable escapement 75 wheel (not shown) located centrally of the machine.

It is to be noted that the carriage release lever 33 and the cast-off lever 20 are both operable by pressure applied at right angles 80 to the longitudinal axis of the platen roll. By this arrangement there is no tendency to effect unintentional longitudinal movement of the carriage when either of these levers is operated. 85

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 90

Having described my invention, what I 95 claim as new and desire to secure by Letters Patent is:

1. In a typewriting machine, in combination, a platen roll, a plurality of feed rollers spring pressed thereagainst, a spring pressed member movable longitudinally of said roll to repress said rollers, an operating lever for said member movable transversely of said roll, and connecting means between said lever and said member comprising a pivoted 105 sub-lever associated with said lever and a rotatable bearing therefor on said member, said sub-lever and said bearing having rolling contact on one side or the other of the diameter of said bearing parallel to the 110 axis of said roll to yieldingly hold said operating lever in one or the other of its extreme positions.

2. In a typewriting machine, in combination, a platen roll, a plurality of paper guide 115 clips spring pressed against the upper part of said roll, a plurality of feed rollers spring pressed against the lower part of said roll and operable to insure movement of said clips away from said roll, and means for 120 moving said rollers away from said roll to move said clips.

3. In a typewriting machine, in combination, a platen roll, a plurality of feed rollers therefor arranged in pairs, the corresponding rollers of each pair being pivotally supported on and eccentric with respect to spaced spindles extending longitudinally of said roll, a plurality of paper clips pivotally supported on one of said spindles, and com- 130

mon operating means to move said rollers and said clips away from said roll.

4. In a typewriting machine, in combination, a platen roll, a plurality of feed rollers therefor arranged in pairs, the corresponding rollers of each pair being pivotally supported on spaced spindles extending longitudinally of said roll, a member extending parallel to said spindles and pivotally supported on one of the same, paper clips longitudinally adjustable on said member, and means to move said member to carry said paper clips away from said roll when said rollers are moved away from said roll.

15 5. In a typewriting machine, in combination, a platen roll, a plurality of feed rollers therefor, a longitudinally extending spindle pivotally supporting said rollers, a plurality of paper clips pivotally supported on said spindle, and a lost motion connection between the supporting means of said clips and the supporting means of certain of said rollers for moving said clips with said rollers when forced out of contact with said roll.

25 6. In a typewriting machine, in combination, a platen roll, a spindle extending parallel thereto and therebelow, a bar extending parallel to said spindle and pivotally connected to the latter by bracket arms at its

ends, paper guides adjustably mounted on 30 said bar, and a spring tensioned between one of said brackets and a fixed part for urging said paper guides toward said platen roll.

7. In a typewriting machine, in combination, a platen roll, an adjacent spindle extending longitudinally thereof, a bracket pivotally mounted on said spindle, a feed roller carried by said bracket, a member extending parallel to said spindle and also pivotally mounted thereon, and a paper guide 35 40 clip mounted on said member.

8. In a typewriting machine, in combination, a platen roll, an adjacent spindle extending longitudinally thereof, a bracket pivotally mounted on said spindle, a feed 45 roller carried by said bracket, a member extending parallel to said spindle and also pivotally mounted thereon, a paper guiding clip mounted on said member, and means to move said member when said bracket is 50 swung in one direction.

In testimony whereof I affix my signature in the presence of two witnesses.

GEORGE GOULD GOING.
